**FROST, SNOW AND SLEET PROTECTIVE COVER
FOR AUTOMOTIVE WINDSHIELD**

Lloyd F. Kurschner, 523 8th Ave.,
Minneapolis, Minn. 55413

Filed Apr. 21, 1969, Ser. No. 16,825

Term of patent 14 years

Int. Cl. D12—14

U.S. Cl. D14—6

FIG. 1

FIG. 2

FIG. 3

FIG. 4

FIG. 1 is a perspective view of a frost, snow and sleet protective cover for automotive windshield, showing my new design.

FIG. 2 is a front elevational view.

FIG. 3 is a rear elevational view; and

FIG. 4 is a fragmentary top plan view.

I claim:

The ornamental design for a frost, snow and sleet protective cover for automotive windshield, as shown.
